[57] CLAIM

The ornamental design for a season ticket issuing machine, substantially as shown and described.

DESCRIPTION

FIG. 1 is a front, top and right side perspective view of a season ticket issuing machine showing my new design;

FIG. 2 is a front elevational view thereof;

FIG. 3 is a right side elevational view thereof;

FIG. 4 is a top plan view thereof;

FIG. 5 is a left side elevational view thereof; and

FIG. 6 is a rear elevational view thereof.

FIG. 7 is an enlarged fragmentary side view of the portion of the control panel circled in FIG. 3; and

FIG. 8 is an enlarged fragmentary top view of the portion of the display panel circled in FIG. 4.

FIG. 1

FIG. 7

FIG. 2

FIG. 3

FIG. 4

FIG. 5

FIG. 6

FIG. 8
